TOOTHBRUSH OR SIMILAR ARTICLE

Allen Schwartz, Brooklyn, N.Y., assignor to Pycope, Inc., Jersey City, N.J., a corporation of Missouri

Filed Dec. 21, 1959, Ser. No. 58,751

Term of patent 14 years

(Cl. D9—2)

The dominant features of my design reside in the portions shown in full lines.

I claim:

The ornamental design for a toothbrush or similar article, as shown and described.
